UNITED STATES PATENT OFFICE

152,330

DESIGN FOR A GLASS TOP END TABLE

Roy A. Dillon, Racine, Wis.

Application November 23, 1946, Serial No. 135,033

Term of patent 14 years

(Cl. D33—14)

To all whom it may concern:

Be it known that I, Roy A. Dillon, a citizen of the United States, and resident of Racine, in the county of Racine and State of Wisconsin, have invented a new, original, and ornamental Design for a Glass Top End Table, of which the following is a specification, reference being had to the accompanying drawing, forming part thereof.

Figure 1 represents a front elevation of an end table showing my new design.

Figure 2 is a rear elevation of the same.

Figure 3 is a top plan view of the table.

Figure 4 is a side elevation of said table.

Figure 5 is a bottom plan view of the table.

Fig. 6 is a perspective view of the table.

I claim:

The ornamental design for a glass top end table, as shown and described.

ROY A. DILLON.
